UNITED STATES PATENT OFFICE.

HORACE RUSSEL ALLEN, JR., OF INDIANAPOLIS, INDIANA.

MEANS FOR SEALING OR UNSEALING CANS.

SPECIFICATION forming part of Letters Patent No. 629,843, dated August 1, 1898.

Application filed November 7, 1898. Serial No. 695,720. (No model.)

To all whom it may concern:

Be it known that I, HORACE RUSSEL ALLEN, Jr., a citizen of the United States, residing at Indianapolis, in the county of Marion and State of Indiana, have invented certain new and useful Improvements in Means for and Methods of Sealing or Unsealing Cans, of which the following is a specification.

The object of my said invention is to provide a means for sealing cans of the variety commonly used for packing and preserving articles of food—such as fruits, meats, relishes, and the like—whereby such cans can be easily and quickly opened when it is desired to use their contents.

In carrying out my invention I use a sealing material which is impervious to air and water, but which will become fluid, preferably by the application of hot water, so that whatever is held thereby will be released.

Referring to the accompanying drawings, which are made a part hereof and on which similar reference characters indicate similar parts, Figure 1 is a perspective view of a can embodying my invention, and Fig. 2 a central sectional view of the same.

In said drawings the portions marked A represent the body of the can; B, the bottom thereof; C, the permanent top; D, a removable cap forming a part of the top, and E a spring arranged within the can and bearing against the under side of the cap.

The portions A and B are or may be of any usual or desired form or construction and need no special description. The top C is also in many respects of an ordinary form, but is preferably given a peculiar formation at its inner edge. Some sealing materials of the character which I design to employ, while perfectly efficient otherwise, do not always adhere to the surfaces to which they are applied as perfectly and strongly as is desirable. I therefore form an annular groove in the inner edge of the top C, which groove is adapted to contain the edge of the cap and the sealing material, and I cause the upper edge c of the outer wall of this groove to overhang its cavity slightly, so that when the sealing material is poured into the groove and becomes set it cannot escape upwardly until it is returned to its fluid condition. The extreme

inner edge c' is curved upwardly a suitable distance to complete the groove.

The cap D is preferably in the form of a disk somewhat concave on its underside, while its edge should be bent downwardly to enter the groove provided therefor around the inner edge of the top C. When inserted in place, the sealing material m is poured around in the groove, sealing the can tightly.

At some suitable point and in a suitable manner within the can, under the cap, I secure the spring E, the upper or free part whereof projects up into the opening to be covered by the cap D. When said cap is put in place, said spring is thereby compressed or forced downwardly. When, however, the sealing material is restored to a fluid condition, this spring acts upon the cap and instantly throws it out of position, thus opening the can. This is a very desirable feature of my invention, as otherwise there would be great danger that the sealing material would become set again after being rendered fluid before the cap could be otherwise removed. I have shown a plain bar-spring in the drawings, but obviously any applicable form of spring may be used.

In sealing a can by my improved method (the contents having, of course, first been placed within the can through the opening in the top) the cap D is placed in the position shown and the sealing material m inserted. When it is desired to open the can, all that is necessary to be done is to pour hot water upon the cap D and the sealing material m until the latter becomes heated sufficiently to be reduced to its fluid condition, when, as above explained, the spring E will instantly throw the cap off. This saves all the labor of cutting through the cap or top with such instruments as can-openers besides saving the can in perfect condition for future use and enabling the cans to be reused indefinitely.

Instead of the hot water I may after filling the groove partially with the fusible sealing material fill the remainder of the space with a combustible material which will constitute a fuse which may be lighted when it is desired to open the can, and the effect will be the same as with the hot water. I prefer, however, to use the material acted upon best

by hot water and to use hot water in the opening operation for the reason that it is more convenient and less expensive, as hot water is always available in kitchens, where cans of this variety are commonly opened.

Having thus fully described my said invention, what I claim as new, and desire to secure by Letters Patent, is—

1. The combination, in a can, of a top for the can having an opening therein with an annular groove formed around said opening, a cap the edges whereof are adapted to be placed within said groove, a spring mounted to bear against the under side of said cap when in place, and a fusible material adapted to be melted by hot water inserted in said groove between the edge of the cap and the surrounding wall of the groove in the top, substantially as shown and described.
2. The combination, in a can, of the top having an opening with an annular groove surrounding the same, a cap adapted to be fitted within said annular groove and there secured by a fusible material, and a spring secured below the cap with its free portion bearing

against the under side of the cap, whereby, when the fusible material is reduced to fluid condition, said spring will operate to throw off the cap, substantially as set forth.

3. The combination, in a can, of the usual body and bottom, a top C having an opening therein with an annular groove around the edges of said opening, the outer wall of said groove overhanging the cavity thereof somewhat, a cap the edge whereof is adapted to be inserted in said groove, a spring mounted to bear against the under side of said cap when in place, and a fusible material adapted to be inserted between the edge of the cap and the overhanging wall of the groove, whereby, when said material is inserted and set it is prevented from separation until returned to a fluid state.

In witness whereof I have hereunto set my hand and seal, at Indianapolis, Indiana, this 31st day of October, A. D. 1898.

HORACE RUSSEL ALLEN, JR. [L. S.]
